JET WASHING PROCESS

Arthur G. Brown, Menlo Park, and Paul H. Wendt, Arcadia, Calif., assignors, by mesne assignments, to Jet Stream Products, Inc., Reno, Nev., a corporation of Nevada

Filed June 5, 1961, Ser. No. 114,898
11 Claims. (Cl. 8—151)

This application is a continuation-in-part of our copending application Serial No. 789,327 filed January 27, 1959, now abandoned.

This invention relates generally to the washing of articles and materials and, more particularly, to a method of washing clothes, yarn, textiles and other pieces of fabric and like materials.

It is anticipated that the invention will be most widely applied in connection with cleaning or laundering operations wherein relatively high speed washing of textile materials and other fabrics is desired. However, it is understood that the invention is of general application and may also find wide application in other operations.

From time immemorial, clothes and like fabrics have been cleaned by subjecting them to mechanical agitation in water, preferably by agitation in the presence of heated water containing a cleaning agent, such as a soap or detergent, or other assists. Although many different methods have been employed for carrying out such operations, they have commonly involved arrangements wherein energy is applied in the washing operation at a relatively slow rate and in an essentially random manner.

A variety of proposals have been made prior hereto for speeding up the washing process. Many of these have never resulted in practical machines because of excessive power, water or chemical requirements, or because the auxiliary mechanical devices required for scrubbing or agitating the cloth would lead to excessive wear. These and other problems commonly encountered have pointed up the need for improved methods, particularly for use in the high speed washing of light weight or delicate fabrics and of clothing and other materials requiring relatively frequent cleaning.

We have discovered that high speed washing of the foregoing and other types of materials may be accomplished by utilizing hydrodynamic forces, without the necessity of employing auxiliary mechanical means for scrubbing or agitating the fabric. We have found that, under certain conditions, the energy and washing fluid requirements can be reduced to very low values and the washing can be accomplished in remarkably short periods of time. For instance, in both home and commercial washing of clothes, it has been quite common to wash the clothes in agitation devices from time periods ranging from 10 or 15 minutes to 35 minutes or even longer. By contrast, in accordance with the present invention, clothes can be cleansed effectively under conditions wherein any small portion of the fabric is exposed to the hydrodynamic action of the wash solution for periods of time ranging from about 1 to about 5 milliseconds, or even less. Thus, it is possible under these conditions for a full-size bed sheet to be thoroughly cleansed in about 4 seconds or less.

A general object of the present invention is to provide an improved method or process useful in washing operations of the type described.

A more specific object of the invention is to provide an improved washing method or process suited for use in high speed washing operations.

2

Another specific object of the invention is to provide an improved washing method or process useful in high speed washing operations performed in connection with the cleaning or laundering of textile and other fabric materials.

5 A further specific object of the invention is to provide an improved washing method or process useful in high speed washing operations performed to remove dirt and other foreign or undesired particles from textile and other fabric materials, the arrangement being such that relatively frequent washing operations may be performed without unduly decreasing the useful life of the materials.

Additional objects and advantages of the invention will be readily apparent from the reading of the following description of the process and reference to the accompanying drawings, wherein:

FIGURE 1 is a chart showing the relationship between the jet velocity wash solution and the efficiency factor of the process at one temperature of the wash solution;

20 FIGURE 2 is a chart similar to the chart of FIGURE 1 showing the relationship between the jet velocity of the wash solution and the efficiency factor of the process at another temperature of the wash solution; and,

FIGURE 3 is a schematic representation showing, 25 mainly in cross section, a laundry machine by means of which the washing process of the invention may be carried on.

In accordance with the invention, the washing of a piece or sheet of fabric material, for example, is accomplished by subjecting successive portions thereof to a stream of washing fluid in the form of one or more high velocity jets. The velocity of each jet is preferably higher than about 360 inches per second. The material is moved across or through the path of the stream which 30 may have a relatively wide dimension in one direction, such as generally cross-wise of the direction of movement of the material with respect to the stream. However, the stream emanates from one or more jet openings having at least one relatively narrow dimension, preferably less than about 0.05 inch, such as generally parallel to the direction of movement of the material with respect to the stream or jet openings.

In a typical application of the invention, the washing of cloth fabric is accomplished by utilizing a stream including one or more narrow jets of wash solution impinging on the cloth at high velocity, the jet or jets being so disposed that a thin high-velocity stream of washing fluid extends across the cloth from one side edge to the other, with the stream sweeping from one end of the 45 fabric to the other as the fabric moves or is advanced through the equipment in a direction generally parallel to the narrow dimension of the jet stream. It will be seen that, under these conditions, each successive portion of the fabric is subjected to a more or less controlled amount of kinetic energy, resulting from the jet action, during 50 a period of time determined by the speed of the cloth, and without random and unnecessary duplication of application of energy. If the velocity of the liquid in the jet stream is maintained above a certain minimum 55 value, as aforesaid, and the thickness or smallest dimension of the jet opening is within a certain range, as aforesaid, it is possible for thorough cleaning of the fabric to be achieved with a relatively low usage of wash solution and expenditure of energy.

60 It will be understood that, in order to handle situations involving a wide variation in degree of soiling from one piece of clothing or fabric to the next, it may be advantageous in many instances to employ more than one of the jet streams. An arrangement may be used whereby

an operator may subject the fabric in some instances to several washing actions, at his discretion. If desired, the usage of the additional streams may be determined by photoelectric or other automatic devices employed for monitoring the degree of soiling, either as initially present or as remaining after each washing action.

The present invention, therefore, lends itself to the employment of completely automatic, continuous machinery in an arrangement whereby a fabric may be inserted into the machine at one end and successive portions of the fabric will be subjected to the cleaning operation, rinsing, bleaching, scouring, and other operations, as well as drying, in a total elapsed time which is relatively short. In fact, the total operation may be accomplished in less than one minute, with the actual cleaning or soil removal operation requiring only a very small fraction of this time and with other washing operations, such as rinsing and bleaching, being likewise accomplished very quickly due to the employment of jet streams in accordance with the invention.

In order to evaluate various washing methods and detergents, standard fabrics which have been soiled in accordance with a prescribed formula are commonly employed. One such formula is that contained in U.S. Bureau of Ships specification 51S-47 (INT), Soil Cloth No. 25 28 wherein white cotton cloth is soiled with lamp black, in a mixture of fats, oils and various hydrophilic colloid substances and baked in an oven, giving a percent reflectance of 26×2 . Such soiled fabrics are extremely difficult to clean and serve as a severe test of washing operations. When such a fabric is subjected to commercial laundry operations wherein it is washed in a conventional rotating drum for a period of 25 minutes, a final reflectance of 50 is the best ordinarily obtainable. A reflectance of 50 indicates that the cotton cloth, with residual soil, reflects 50% as much white light as a magnesium oxide standard when measured in a standard reflectometer.

In order to demonstrate the drastically different result which is obtained when the process of the present invention is used, as compared with prior art processes, standard dirty samples of cloth were washed in a machine in which a high velocity jet stream of hot wash solution impinged upon the cloth at various jet velocities and for various contact times. The solution was maintained at 45 a temperature of 160° F. and consisted of 0.03% of a high titer soap and 0.006% alkali (anhydrous orthosilicate). A high pressure pump was employed to drive the washing solution against and through the cloth as the cloth was moved under the jet stream. By varying pressure of the jet stream, the speed at which the cloth is moved, and the number of passes of the cloth (number of jet streams) one can arrive at the amount of washing required to secure a given cleaning effect or reflectance. For the purpose of the present study, a reflectance value 50 of 50 was selected as being typical of present commercial laundering practice. From experiments in which the jet stream velocity and the contact time were varied the conditions required to give a reflectance reading of 50 could be determined. One can then calculate the amount of 60 energy which was applied to each unit area of cloth to secure the desired cleaning effect, and also the amount of solution employed. When samples of standard dirty cloth were washed under various conditions, the data in Tables I and II were obtained.

In these tables, the headings indicate:

v—Jet stream velocity in inches per second.

h—Jet stream thickness in mils (thousandths of an inch).

V—Cloth velocity in feet per minute.

E—Energy applied in joules per square inch.

T—Contact time in milliseconds.

G—Volume solution in gallons per square inch times one hundred.

EG—Efficiency factor (E $\times$ G).

The jet stream velocity, v (in./sec.) is related to the measured flow rate, F (gal./min.), by the relation

$$v = 3850F$$

where h is the thickness of the jet stream in mils and 1 its width in inches (usually the width of the fabric being cleaned).

The contact time, or residence time, T (in milliseconds) is defined by the relation

$$T = \frac{5Nh}{V}$$

where N is the number of passes (jet streams) required to accomplish a cleaning corresponding to a reflectance of 50 and V is the velocity of the cloth (ft./min.) in passing through the jet streams.

The energy (joules/in.²) applied to the fabric to achieve a reflectance of 50 is given by

$$E_{50} = \frac{1480N.F^3}{V.h^2.1^3}$$

at a temperature of 160° F. where F , 1, h , N , and V have the same definitions as above.

The volume of wash solution required (per sq. in. of fabric) to achieve a cleaning corresponding to a reflectance of 50, is calculated from the relation

$$G_{50} = \frac{N}{12V} \times \frac{F}{1}$$

where the symbols have their previous meanings and units.

In practice, both the total energy requirements and the amount of wash solution applied to the material must be kept at a minimum. The overall efficiency of the process can therefore be described in terms of a cost factor $E_{50}.G_{50}$ obtained by multiplying together the numbers shown for these quantities in Table I. FIG. 1 shows a summary of these data, together with additional data from a large number of experiments, plotted to show the relationship between the overall cost factor and the jet stream velocity v . FIG. 2 shows the same relationship for a wash solution at 190° F. containing 0.1% high titer soap and 0.02% alkali. In accordance with the present invention the washing is carried out under conditions whereby an EG value of not over 30 is employed.

It will be seen from the graphs that when the velocity of the jet stream is low, large amounts of energy and of wash solution are required and the process is inefficient. As the velocity of the jet stream is increased to a value of about 360 in./sec., the amounts of energy and of wash solution suddenly drop to very low values and one suddenly achieves a high degree of cleaning efficiency.

We have therefore found that if the fabric is exposed to a jet stream of the kind described, in which the velocity of the stream is greater than about 360 in./sec., an extremely efficient cleaning action is achieved in a short amount of time and at a low total expenditure of energy and wash solution. This, in turn, enables one to provide for an automatic, continuous washing machine which has heretofore not proved practical.

The jet stream employed may be obtained from a nozzle in the form of a single, long, narrow slot set at right angles to the path of travel of the material through the machine. Although a single thin jet stream impinging on the cloth from one side edge to the other and sweeping along the length of the cloth as it passes under the jet is so obtained, it will be recognized that equivalent or otherwise suitable action can also be obtained using various other arrangements. For instance, it may be advantageous for the jet stream, in order to achieve mechanical strength and simplicity in the nozzle, to be provided by a staggered series of flat jets located alternatively forward and backward of the center line of the nozzle structure and so disposed that essentially no overlap of the jets occurs.

The jet or jets forming the stream are preferably obtained from one or more nozzles having thin slots or other openings extending from about 5 to about 50 mils (thousandths of an inch) in the dimension thereof parallel to the general direction of movement of the fabric

with respect to the nozzle structure when the fabric is passing across the path of the jet stream. The narrower openings are preferable in that conditions for efficient cleansing are more readily achieved, but the openings are limited in minimum thickness by practical considerations of hazard of plugging from lint or other particles accumulating in the wash solution.

The distance between the jet nozzle and the material being washed is preferably small and may be 1½ inches or smaller in some instances. It is important that the nozzle be placed close enough to the material being washed so that the jet stream particles do not break up into relatively slow moving droplets before striking the cloth being washed, i.e., it is important to have a continuous jet action against the cloth; otherwise, some of the energy of the jet stream is lost and the overall efficiency of the operation is thereby decreased. Experiments have shown that a jet stream velocity higher than about 360 inches per second can be maintained with a nozzle-to-fabric distance ranging from less than 1½ inches upward, with considerable success being obtained at distances of about 7 inches using readily available pumping equipment to develop pressure in the nozzle.

It can be seen from the examples in the tables and in the figures that greater cleaning efficiencies are achieved if the velocity of the cloth through the machine is relatively high. We prefer to carry out our washing process at cloth speeds of about 50 ft. per min. or greater. In a unitary piece of laundry equipment used for washing, ironing, etc., in a continuous process, an upper limit of velocity of the cloth of around 100 ft./min. is presently set by the speed of commercial ironing equipment which might be employed in conjunction with our process, but it will be recognized that speeds much greater than this could be efficiently employed.

Where water is used as the washing medium, the temperatures can be those which are readily available in commercial laundries, e.g., from 140° F. to 180° F., or higher. Conventional detergents or soaps and washing assists may be employed as in present laundry practice. It will be recognized that, although particular reference has been made to the cleaning of fabrics or clothes with aqueous wash solutions, the invention is not limited to such systems and may also be applied to the cleaning of other more or less porous or even solid materials. Also, the invention may make use of other cleansing fluids, such as hydrocarbons, chlorinated hydrocarbons and the like, with or without soaps or other assists, as in dry cleaning or other processes.

FIGURE 3, which forms a part of this application, shows a practical embodiment of a machine which employs the principles of the present invention. This machine is obviously not the only machine which can be employed to carry out the process of the present invention. Among others which can be employed, for example, are those wherein the fabric is carried on a perforated drum or hung over a line which moves continuously and exposes the fabric to the washing process while it is held in a vertical position.

Turning now to a description of the machine shown in FIGURE 3, the machine has a housing 4 with an entrance port 6 and an exit port 8. Two endless belts, 10 and 12, are provided for initially conveying the clothes into the washer. These belts are driven in synchronism by conventional means not shown and the lower belt 12 extends outside of the machine over the pulley 14 so that fabrics can be placed thereon and transported into the machine.

As illustrated, each of the belts 10 and 12 is formed of parallel stainless steel wires. In this manner, it is simple to provide interlocking belts so that several relatively short runs of belts can be used in the machine rather than single long runs.

As the cloth enters the machine, it is acted upon first by the streams emanating from jet 16 and jet 18, each of which is shown as a two-headed jet. The material is

thus subjected to a total of four jet streams as it passes jets 16 and 18. It will be understood, however, that the number of jet streams employed might be smaller or larger.

These jet streams are shown supplied from a tank 20 containing wash solution, which is passed through the pump 22 and filter 24 and through the line 26 into the jets. After the solution has passed through the material, it drops back into the wash solution tank 20. Although not shown, it is understood that means can be provided for replenishing the solution and also for heating it.

After the cloth passes through the first jets, it is picked up by a second set of belts, 28 and 30, and passed under a rinsing jet 32. This jet is supplied with water from the tank 34 through the pump 36. The cloth is next subjected to the bleaching solution from jet 38 and is passed over the drums 40 and 42, which are shown as relatively large drums used to allow the bleaching solution sufficient time to act. It will be noted that the bleach solution is supplied from tank 37 through pump 39.

The cloth then passes under the rinse jet 44, which is shown supplied with water from the rinse tank 46 through the pump 48. At this point, the material is picked up by a third set of belts 51 and 53. The material then passes through the drying chamber, generally designated 50, where it passes over the relatively large drums 52 and 54 while air is constantly circulated through the chamber by means of fan 56 which passes the air through the heater and dehumidifier 58. The cloth, which has been subjected to continuous washing, rinsing, bleaching and drying operations, is then discharged from the port 8.

Obviously, many modifications and variations of the present invention are possible in the light of the above teachings. It is therefore to be understood that within the scope of the appended claims the invention may be practiced otherwise than as specifically described.

We claim:

1. A process of washing fabric materials comprising: supporting the fabric material on a movable rigid support, moving the support and fabric material to be washed across the path of a jet stream of washing fluid to subject successive portions of the fabric material to the jet action of the stream, said stream emanating from an unsubmerged source at a velocity of at least 360 inches per second, said stream having a relatively wide dimension in one direction but emanating from at least one opening having a narrow dimension not greater than about 0.05 inch.

2. A process of washing fabric material comprising: supporting the fabric material on a movable rigid support, moving the support and fabric material to be washed across the path of a jet stream of washing fluid to subject successive portions of the fabric material to the jet action of the stream, said stream emanating from an unsubmerged source at a velocity of at least 360 inches per second, said stream emanating from at least one jet opening having a narrow dimension not greater than about 0.05 inch extending in a direction generally parallel to the direction of movement of the fabric material with respect to said opening, said stream having a relatively wide dimension extending in a direction generally cross-wise of the direction of movement of the fabric material with respect to said opening.

3. A process of washing fabric materials comprising: supporting the fabric material on a movable rigid support, continuously moving the support and fabric material to be washed across the path of an unsubmerged jet stream of washing fluid to subject successive portions of the fabric material to the jet action of the stream; said stream including at least one jet emanating from an opening having one dimension not greater than about 0.05 inch measured in a direction generally parallel to the direction of movement of said fabric material with respect to said jet opening, and said jet emanating from

said opening at a velocity of at least about 360 inches per second.

4. A process of washing fabric materials comprising: continuously moving the material to be washed across the path of an unsubmerged jet stream of washing fluid to subject successive portions of the material to the jet action of the stream, supporting the fabric material on a rigid support at the point where said jet stream strikes the fabric material, said stream being in the general form of a narrow, elongated rectangle when viewed in cross section and including at least one jet emanating from an opening extending in the direction of the narrow dimension of said stream a distance not greater than about 0.05 inch, and said jet emanating from said opening at a velocity of at least about 360 inches per second.

5. A process of washing fabric materials comprising: sweeping portions of the material with a jet stream of washing fluid, supporting the fabric material on a rigid support at the point where the jet stream sweeps the fabric material, said stream being in the form of a narrow, elongated rectangle when viewed in cross section, said stream including at least one jet emanating from an unsubmerged opening disposed in spaced-apart relation to the material, and extending in the direction of the narrow dimension of said stream a distance not greater than about 0.05 inch, and said jet emanating from said opening at a velocity of at least about 360 inches per second.

6. A process of washing fabric materials comprising: moving a material to be washed across the paths of a plurality of jet streams of washing fluid in succession to subject successive portions of the material to the jet action of each of the said streams, supporting said material on a rigid support at each point where a jet stream strikes the material, each of said streams including at least one jet emanating from an unsubmerged opening extending in a direction generally parallel to the direction of movement of said material a distance not greater than about 0.05 inch, and said jets each emanating from its opening at a velocity of at least about 360 inches per second.

7. A process as defined in claim 6 wherein the plurality of jet streams direct washing fluid against both the opposite sides of the material.

8. A process for washing fabrics comprising: supporting a fabric to be cleaned on a rigid support and advancing said fabric thereon beneath a jet of washing fluid, said jet consisting of a narrow, elongated rectangle when viewed in cross section, said fabric being advanced in a direction parallel to the narrow dimension of said jet, said jet having a maximum thickness through the narrow dimension thereof of 50 mils, said jet emanating from a source spaced from the point of impact upon said textile material no more than 1½ inches, and emanating from said source at a velocity of at least about 360 inches per second, said fabric being advanced at a velocity such that the total energy applied to each square inch of said fabric being cleaned by the action of said jet of washing fluid is at least one joule, the speed of travel of the fabric through the machine being greater than 50 ft./min.

9. A process for washing fabrics comprising: supporting a fabric to be cleaned on a rigid support and advancing said fabric thereon beneath a jet of washing fluid, said jet consisting of a narrow, elongated rectangle when viewed in cross section, said fabric being advanced in a direction parallel to the narrow dimension of said jet, said jet having a maximum thickness through the narrow dimension thereof of 50 mils, said jet emanating from a source spaced from the point of impact upon said textile material no more than 1½ inches, and emanating from said source at a velocity of at least about 360 inches per second, said fabric being advanced at a velocity such that the total energy applied to each square inch of said fabric being cleaned by the action of said jet of

washing fluid is at least one joule, the wash solution containing an organic solvent.

10. A process for washing fabrics comprising: supporting a fabric to be cleaned on a rigid support and advancing said fabric thereon beneath a jet of washing fluid, said jet consisting of a narrow, elongated rectangle when viewed in cross section, said fabric being advanced in a direction parallel to the narrow dimension of said jet, said jet having a maximum thickness through the narrow dimension thereof of 50 mils, said jet emanating from a source spaced from the point of impact upon said textile material no more than 1½ inches, and emanating from said source at a velocity of at least about 360 inches per second, said fabric being advanced at a velocity such that the total energy applied to each square inch of said fabric being cleaned by the action of said jet of washing fluid is at least one joule, the washing being conducted under conditions whereby an EG value of not over 30 is employed wherein E is the energy in joules applied to each square inch of cloth, and G is the number of gallons of wash solution applied to each 100 square inches of cloth.

11. A process for washing fabric materials comprising: supporting a fabric to be cleaned on a rigid support and advancing said fabric thereon beneath a plurality of jets of washing fluid, each of said jets consisting of a continuous, narrow, elongated rectangle when viewed in cross section, said fabric being advanced in a direction paral-

10
lel to the narrow dimension of each of said jets, each of said jets having a maximum thickness through the narrow dimension thereof of 50 mils, each of said jets emanating from an unsubmerged source spaced from the point of impact upon said fabric no more than 1½ inches, and emanating from said sources at velocities of at least 360 inches per second, said fabric being advanced at a velocity such that after passage beneath all of the said jets, said fabric will have had imparted to each square inch of fabric being cleaned a total energy of at least one joule through the action of said jets of washing fluid.
